[57] CLAIM

The ornamental design for a carrying handle for sewing machine, substantially as shown and described.

DESCRIPTION

FIG. 1 is a perspective view of a carrying handle for sewing machine showing our new design, the broken line showing of a sewing machine being for environmental purposes only;

FIG. 2 is a perspective view of the handle in carrying position, the broken line showing of a sewing machine being for environmental purposes only;

FIG. 3 is an end elevational view, the opposite end being identical thereof;

FIG. 4 is a front elevational view thereof;

FIG. 5 is a rear elevational view thereof;

FIG. 6 is a top plan view thereof; and

FIG. 7 is a bottom plan view thereof.
